UNITED STATES PATENT OFFICE.

EDWIN GORDON, OF HYDE PARK, MASSACHUSETTS.

RAILROAD-SWITCH.

SPECIFICATION forming part of Letters Patent No. 377,713, dated February 7, 1888.

Application filed April 25, 1887. Serial No. 235,995. (No model.)

To all whom it may concern:

Be it known that I, EDWIN GORDON, a citizen of the United States, residing at Hyde Park, in the county of Norfolk and State of Massachusetts, have invented certain new and useful Improvements in Railroad-Switches; and I do hereby declare that the following is a full, clear, and exact description of the invention, which will enable others skilled in the art to which it appertains to make and use the same.

The object of my invention is a railroad-switch so constructed that in case it is misplaced it will be moved into place by the passing train, and thus prevent derailment; and it is an improvement on the invention described in Letters Patent to me, No. 348,006, dated August 24, 1886. As in the Letters Patent referred to, I accomplish the switching by the use of two fixed point-rails, each being in connection with a pair of jointed continuous switch-rails and with guard-rails, the opposite jointed middle ends of the switch-rails being connected and firmly held there at gage, the outer ends being fished to fixed track-rails. The switch is set for the main track or siding by a lateral movement of the switch-rails at the point where they are connected.

In the drawings I have shown in Figure 1 a plan of my improved switch. Fig. 2 is an enlarged partial section on line $y'y'$, Fig. 1. Fig. 3 is an enlarged section on line $x'x$, Fig. 1, the switch-rod, Fig. 1, and connecting-link being left in elevation. Fig. 4 is an enlarged section on line $y'y$, Fig. 1. Fig. 5 is an enlarged section on line $z'z$, Fig. 1. Fig. 6 is a section on line $x'x'$, Fig. 3. Figs. 7, 8, and 9 are enlarged views in detail illustrating the operation of the mechanism for shifting and locking the rails. Fig. 10 is a perspective view of a locked switch-stand and signal-stand.

$A A^3 A^2 A^2$ are continuous jointed rails.

$C C'$ are fixed point-rails firmly attached to the ties, so as to permit of no motion.

$D D$ are guard-rails bolted to the continuous rails and movable therewith, with the ends reaching across the point of junction of the continuous rails, and so placed as to prevent the wheel-flanges of the locomotive or cars from coming in dangerous contact with the

ends of the point-rails. Each pair of the movable rails, with one end of a guard-rail, is fastened together, as described in the said patent, by placing a block, e , of cast iron or steel about twelve inches long, between the guard-rails and the switch-rail ends, the center of the block as to its length being placed opposite to the point where the rail ends meet. A block of the same length is also placed opposite on the other side of the rail ends, and one opposite on the other side of the guard-rail. These three blocks conform to the shape of the sides of the rails, except that one of them is slightly cut away at an angle from the center, to permit of the required lateral motion of the switch-rails. The two outside blocks have a bearing on a line with the bottom of the connected switch-rail ends and the guard-rails, and the guard-rails and the several parts, as described, are firmly fastened together by the bolts $c c$. The center block is of such a width as will hold the guard at that point at a distance less than the distance between the point of the point-rail and the contiguous switch-rail when the switch is open for the main track, as in Fig. 1. The point end of the other point-rail is protected by lying in the angle formed by the contiguous switch-rail, and is outside the running line, as shown in said figure. The conditions, thus preventing the wheel-flanges from coming in dangerous contact with the point ends, are reversed when the switch is thrown in connection with a branch track or siding. These connected parts rest upon the bar s , with side pieces or flanges, e^2 , Fig. 3, riveted or welded to it and turned up at right angles, thus holding the rails at that point at gage, and with the bolts hold the connected parts firmly together, the side pieces, e^2 , being also especially useful in preventing the parts from separating in case the bolts should become loose, but do not prevent the rails from moving longitudinally. In the center of the piece h is a pin passing through the end of lever f , Fig. 1, pivoted at g , and which is there held in place by the cap b' , bolted to the plate c' , fixed to the tie beneath, as shown in Fig. 5. One end of the lever f is adapted to connect with the eyebolt k , secured to the switch-bar f' . The other end of the lever connects by means of the pin i with the cross-piece h , the

construction of which is illustrated by the section shown in Fig. 2.

h' h' are pieces of iron, so made and secured as to prevent the cross-piece from getting out of place. The switch-bar *f'* is connected at one end to a hand-lever, *g'*, Fig. 10, pivoted at *h'* to a stand, *i'*, the upper end of said lever *g'* being inclosed in a wire cage, *j'*, provided with a locked door, *k'*. To the hand-lever *g'* is attached a rod, *l'*, which, by means of the connecting-arm *m'*, is adapted to give a quarter of a revolution to the upright rod *n'*. To the upper end of this rod *n'* is attached the ordinary signal. At the opposite end the switch-bar *f'* is attached to a link, *o'*, by a stud, *p'*. Said link *o'* is pivoted at *q'*, the pivot passing through a boss in the fixed bar *r'*, and is secured to the parallel link *v'*. The link *o'* is connected with the bar *s'* by means of the pin *t'*, which passes through a boss in the bar *s'*, which pin is secured to the link *v'*, as shown. The width of the bar *r'* and bar *s'* corresponds with the width of the space between the parallel links.

It will be seen that when the switch-rod *f'*, Fig. 1, is moved from the position there shown, to shift the switch from the main to the branch track, the connected links *o'* and *v'* are pulled over or turned on the pivot *q'* and left in the act of turning one end of the bar *s'* half an inch from the fixed bar *r'*, (see Fig. 7, showing the position of the bar *s'*,) with throw half made, and completing the throw. The switch-bar, in connection with the link *o'*, is shown in Fig. 9. Thus it will be seen that there can be no lateral movement of the switch—*i. e.*, it cannot be thrown from the main track onto the branch track or back onto the main track without at the same time lifting one end of the bar *s'*, as described. Consequently no lateral movement is possible when a train is passing.

Another feature in my invention is that if the switch should not be fully thrown the weight of the locomotive will force down the bar *s'* and thus complete the throw.

The switch being open for the main track,

the wheel-flanges will not come in contact with the cross-piece *h*, as there is then a clear space between the heel-connection of the point-rail *C* and the contiguous end of the cross-piece *h*. If, however, a train comes from the branch track, the switch being set for the main line, the first wheel-flange will come in contact with the cross-piece at *a'* and impart a lateral motion, thus giving, through the lever *f*, the required motion to the switch-bar, as before described, and the switch is thus shifted into connection with the siding. Being thus left misplaced for the main track, a train coming along in the same direction on the main track, the first wheel-flange will come in contact with the cross-piece *h*, Fig. 1, at *a'*, and impart the required lateral movement, and then, through the lever *f*, the switch-bar is moved and the track is open for the train. As the switch is thrown by hand, the cross-piece, through the lever-connection with the switch-bar, is moved so as to be acted upon automatically when the switch is misplaced either for the main line or for the branch track by trains passing in the direction off the points not toward them.

What I claim, and desire to secure by Letters Patent, is—

1. In a railroad-switch, the continuous switch-rails *A A' A'*, the blocks *e e*, the bolts *c*, the guard-rails *D*, the bar *s'* and bar *r'*, links *o'* and *v'*, the pivot *q'*, and bolt *t'*, stud *p'*, and switch-bar *f'*, in combination with the fixed point-rails *C C'*, substantially as and for the purpose above described.

2. In a railroad-switch, the continuous rails *A A' A'*, blocks *e e*, bolts *c*, guard-rails *D*, bars *s'* and *r'*, links *o'* and *v'*, pivot *q'*, and bolt *t'*, in combination with the device for automatically moving the continuous switch-rails, consisting of the lever *f* and the cross-piece *h* and the piece *h'*, substantially as and for the purpose above described.

EDWIN GORDON.

ESTELLA BARRY.

Correction in Letters Patent No. 377,713.

It is hereby certified that in Letters Patent No. 377,713, granted February 7, 1881, upon the application of Edwin Gordon, of Hyde Park, Massachusetts, for an improvement in "Railroad Switches," an error appears in the printed specification requiring correction, as follows: In line 32, page 2, the parenthetical mark after the referred letter "s" should be stricken out and the same inserted after the word "made" at the end of said line; and the said Letters Patent should be read with this correct therein that the same may conform to the record of the case in the Patent Office.

Signed, countersigned, and sealed this 12th day of March, A. D. 1889.
